[57] **CLAIM**

The ornamental design for a combined radio and disc player, as shown and described.

DESCRIPTION

FIG. 1 is a perspective view of a first embodiment of a combined radio and disc player showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof;

FIG. 8 is a perspective view of a second embodiment of a combined radio and disc player showing my new design;

FIG. 9 is a top plan view of the embodiment of FIG. 8;

FIG. 10 is a left side elevational view of the embodiment of FIG. 8;

FIG. 11 is a front elevational view of the embodiment of FIG. 8;

FIG. 12 is a bottom plan view of the embodiment of FIG. 8;

FIG. 13 is a right side elevational view of the embodiment of FIG. 8;

FIG. 14 is a rear elevational view of the embodiment of FIG. 8; and,

FIG. 15 is a perspective view of the embodiment of FIG. 8, shown in an open position.

The views of the inside of the combined radio and disc player form no part of the claimed design.
